ROTARY FUEL DISTRIBUTING VALVE

George L. Nies, Ephrata, Pa.

Application February 27, 1945, Serial No. 579,953

2 Claims. (Cl. 137—146)

1

This invention relates to valves of the rotary type to deliver uniform charges of fuel to the working cylinders of internal-combustion engines in the quantities required by the speed of the engine and the load to which it is subjected.

It is an object of the invention to provide a valve structure having few parts that are economical to make, to assemble, to operate, and to disassemble for cleaning and renewal, and yet highly efficient in its functioning.

Another object of the invention is to provide a valve structure of this kind in which a single part rotating at the same speed as the crank-shaft of the engine with which it is associated feeds to every engine cylinder, with every rotation of the crank shaft, equal quantities of fuel during any speed and under any load at which the engine may be operated.

The valve structure is adapted for use with prime movers of the Diesel and other types in which fuel is forced under pressure to the engine cylinders, the speed of the pump determining the amount and compression of fuel supplied to the valve structure and thus the quantity of fuel delivered to the cylinders in any circumstances of speed, engine load, and other factors.

Moreover, the valve structure also is capable of correspondingly functioning in association with internal-combustion engines into the cylinders of which the fuel is drawn by suction and electrically ignited.

With either type of engine, the valve structure has only one moving part, which rotates continuously while the engine is operating. This part, being essentially one that rotates continuously in one direction and does not reciprocate or oscillate, does not require cam-actuated rods, and is free of discs, springs, and other parts such as needed for pop-valves and other reciprocating charge controlling elements. Moreover, the feeding of fuel to the engine cylinders is with uniform flow and is continuous at the moments every valve-port is open, and no flow control by a series of measuring drums or other auxiliary is required.

Further, when an engine of a certain number of cylinders requires a valve structure of this invention and the only one then available is for an engine of a greater number of cylinders, the valve structure easily can be adapted to the lesser number.

When considered with the description herein, characteristics of the invention are apparent in the accompanying drawing, forming part hereof, wherein an adaptation in association with a six-

2

cylinder engine is disclosed for purpose of exemplification.

Like reference characters refer to corresponding parts in the views of the drawing, which—

5 Fig. 1 is a longitudinal axial section, parts of the engine cylinders being shown diagrammatically;

Fig. 2 is an enlarged section on line 2—2, Fig. 1; Fig. 3 is a flattened plan view of the rotor indicating positions of the ports thereof.

10 The valve structure includes a casing 4, which usually is cylindrical outside, and the inner surface of the wall of which is circular and machined smooth to uniform diameter from end to end. The casing has a plurality of equally spaced exit passages 5 in its wall leading from the inside to the outside thereof. The inner ends of the passages preferably are disposed in a straight line parallel to the axis of the chamber.

15 The casing is held against rotation in any suitable manner, as by supporting elements 6.

20 A rotor 7 turns inside of the casing. It comprises a hollow cylinder 8, which is machined smooth on the outside and is of exterior circumference to give it a tight running fit against the inner surface of the casing. The cylinder contains a fuel chamber. The cylinder is closed at one end by a plug 9 tightly fitted into it and extending outside thereof. The plug has an annular exterior flange 10, which is welded to the end of the cylinder 8 and is of the same circumference as the inside of the casing 4 in which it turns. A drive element, such as a gear wheel 11, is fast on the exterior portion of the plug.

25 30 A wall 12 closes the cylinder 8 at its other end. An annular flange 13 on that end of the cylinder runs against the end of the casing 4.

35 40 A fuel supply pipe 14, which is held fixed against rotation in any suitable manner, extends through the wall 12 in the axis of the cylinder. That wall is recessed outside, and packing 15 in the recess around the pipe is compressed by a gland 16, which is held on the end of the cylinder by bolts 17.

45 50 The rotor turns in bearings 18 on one end thereof and on the plug, the bearings being held by suitable means, as by supports 19.

55 Exit ports 20 extend radially from the chamber of the cylinder through the wall to the periphery thereof. The ports used are of the same number and are spaced to become aligned at their outer ends with the exit passages 5 of the casing as the cylinder rotates. The exterior or passage aligning ends of the ports are disposed at the periphery of the cylinder in such places

that they come to alignment and communication with the exit passages one at a time and successively between equal intervals of port closure by the rotor as it turns.

This may be attained by placing the port ends in a straight line disposed at an angle to the axis of the rotor; for example, in an angle such as shown diagrammatically in Fig. 3. However, the peripheral ends of the ports may be arranged in any other suitable manner, that is they may be spaced both circumferentially and longitudinally of the rotor so that only one of them at a time will become aligned with a casing passage and the intervals between successive alignments and passage of fuel into the exit passages is uniform.

Moreover, although the passages 5 are referred to as being equally spaced and disposed in the wall of the casing in a straight line and the cylinder ports as being correspondingly disposed, it is within the concept of this invention to employ different arrangements. The criterion is that one arrangement of either the passages or ports having been established, the arrangement of the others must be in consonance therewith to give sequential registry of them at proper times.

The casing passages 5 are connected by pipes or other conduits to supply fuel to engine cylinders. Fig. 1 illustrates diagrammatically association of my valve structure with a six-cylinder engine, whose cylinders are designated by 21, and the connections thereof with the passages by lines 22.

It is to be understood that the valve structure is adaptable for association with engines of more or less numbers of cylinders by forming the casing and cylinder, respectively, with the number of exit passages and ports required. Moreover, if my valve structure has more passages and ports than required for a particular engine, the excess may be plugged or otherwise rendered inoperative.

The fuel comes into the cylinder 7 through the supply pipe 14. The cylinder is rotated, by suitable drive means, at the same speed as the engine crank shaft. Fuel leaves through the casing passages at proper time successively to the cylinders of the engine in quantities required by the engine.

I claim:

1. A valve structure of the kind and for the purpose described comprising an elongated fixed casing with a smooth inner cylindrical surface and having spaced exit passages extending from its interior to the exterior and capable of being

in communication with cylinders of an engine, an elongated hollow fuel-chamber-containing rotor in and having tight running fit with the cylindrical surface of said casing, a rotatable plug tightly fitted into and closing one end of said rotor, an annular flange on said plug having tight running fit at its periphery with the inner surface of said casing, a wall closing the other end of said rotor, an annular flange on that end 10 of said rotor having tight running fit with the corresponding end of said casing, a fuel supply pipe extending axially through said wall, and means associated with said plug to rotate said rotor, said rotor having spaced ports in its periphery positioned to align successively with the exit passages of said casing during continuous rotation of the rotor.

2. A valve structure of the kind and for the purpose described comprising an elongated fixed casing with a smooth inner cylindrical surface and having spaced exit passages extending from its interior to its exterior and capable of being in communication with cylinders of an engine, an elongated hollow fuel-chamber-containing cylindrical rotor in and having tight running fit with the inner surface of said casing, a rotatable plug tightly fitted into and closing one end of said rotor and extending outside thereof, an annular flange on said plug having tight running fit at its periphery with the inner surface of said casing, a wall closing the other end of said rotor, an annular flange on that end of said rotor having tight running fit with the corresponding end of said casing, bearings in which said rotor turns one being on said plug and another on said rotor at its other end, means associated with said plug to rotate said rotor, and a fuel supply pipe extending axially through the closing wall of said rotor, said rotor having spaced 20 ports extending from its chamber to its periphery positioned to align successively with the exit passages of said casing during continuous rotation of the rotor.
